GEORGE PRIFOLD, OF SOMERVILLE, NEW JERSEY.

ART OF PRINTING RUGS.

Application filed January 3, 1927. Serial No. 158,456.

This invention relates to an improvement in the art of printing rugs, and particularly rugs made from floor covering in strip form and printed by means of a block printing machine before they are cut from the strip.

An object of the invention is to print more complicated designs than have heretofore customarily been used without materially increasing the number of printing blocks required, and more particularly to provide for printing a center figure on a rug without providing special blocks for this purpose.

15 A further object is to provide for printing symmetrical center-figure rugs of any desired length from a single set of printing blocks.

In making rugs from floor covering in strip form, such as linoleum, oilcloth, and the like, it has been customary to pass a continuous strip of material through a block printing machine containing blocks which are supplied with paint, and are timed to 20 print on various zones of the strip to produce the required design. The strip is thereafter cut into rugs. As such rugs are ordinarily provided with borders including end borders extending across the strip and side borders extending along the edges of the strip, two sorts of printing blocks are provided. They are the end-border blocks, and the side-border-and-field blocks. The latter are impressed upon the zones of the strip between each two impressions of the end-border blocks, so that the design printed between the end borders consists of the regular repetition of a figure.

According to the present invention, the 25 monotonous regularity of a repeated figure is relieved by providing each rug with a center figure, and also, if desired, with an end figure; and by means of a set of blocks carrying asymmetric and symmetrical designs whose edges fit together, provision is made for producing symmetrical center-figure rugs of any desired length.

The nature of the invention will more fully appear from a detailed description of 30 a simple illustrative method and apparatus embodying it. This simple illustration, which provides for printing a very simple design in only one color, will serve to indicate to those skilled in the art, the manner in which the invention may be applied to

the printing of complicated designs using any desired number of colors. In the detailed description I shall refer to the accompanying drawings, in which:

Fig. 1 is a bottom view of a set of five 60 printing blocks, indicating diagrammatically the upper portion of a conventional block printing machine on which the blocks are mounted;

Figs. 2 and 3 show strips of floor covering printed from said set of blocks; and

Figs. 4 to 11 show, on a smaller scale, rugs of different lengths printed from said set of blocks.

The set of blocks shown in Fig. 1 includes 70 an end-border block 1, an end-figure block 2 carrying an asymmetric design, and a similar block 3 carrying the same asymmetric design turned in the opposite direction, a center-figure-fill-in block 4 carrying a symmetrical design, and a field-fill-in block 5 also carrying a symmetrical design.

The end-border block 1 carries a pair of 80 end-borders 1^a, which together occupy the entire width of the block.

The end-figure blocks 2, 3 carry side-border sections 2^a, 3^a and asymmetric middle figures 2^b, 3^b, and may in addition have intermediate figures 2^c, 3^c which may also be asymmetric. The middle figures 2^b, 3^b 85 extend to the side edge *a* of each block. The intermediate figures 2^c, 3^c may extend to each side edge *a*, *b* of each block; and if desired, the middle figures 2^b, 3^b could be extended to the side edge *b*.

The center-figure-fill-in block 4 carries the side-border sections 4^a, 4^b and a symmetrical middle figure 4^b which extends across the width of the block. This block may also be provided with symmetrical intermediate 95 figures 4^c. Each side edge of the symmetrical design on the block 4 fits the side edge *a* of the asymmetric design on the blocks 2 and 3.

The field-fill-in block 5 carries side-border 100 sections 5^a and symmetrical figures 5^c. Each edge of the symmetrical design on the block 5 fits the edge *b* of the asymmetric design of the blocks 2 and 3.

In printing rug designs by means of the 105 blocks described, the set of blocks is placed in a block printing machine of the usual type, and a strip 10 of floor covering is passed under them. In order to print rug designs having a center figure and end 110

figures as shown in Fig. 2, spaced pairs of the asymmetric designs of the blocks 2 and 3 are printed along the strip with their edges *a* turned toward each other. Thus as shown in Fig. 2, one such pair is formed by impressing the block 2 on the zone A of the strip, and impressing the block 3 on the zone C of the strip. The next pair is formed by impressing the block 2 on the zone A' 5 and the block 3 on the zone C', and the next by impressing the block 2 on the zone A'', and the block 3 on the zone C''. The middle space of each alternate pair of such impressions is filled in to form a center 10 figure by the symmetrical design of the block 4. Thus in Fig. 2, the block 4 is impressed on the zone B', so that its impression cooperates with the impressions of the blocks 2 and 3 on the zones A', C' in forming a center figure 11 made up of the figures 2^b, 4^b and 3^b. The middle space of the other alternate pairs of impressions from the blocks 2 and 3 is filled by pairs of end 15 borders, so that the figures 2^b, 3^b of such alternate pairs become, in each rug printed, end figures projecting inwardly from the end borders, and cooperating therewith to provide end-border designs. For this purpose, the block 1 is impressed upon the zones 20 B and B'' in Fig. 2.

If, as shown in Fig. 2, spaces are left between the pairs of impressions of the blocks 2 and 3, such spaces are filled by impressions of the symmetrical design of the block 5. 25 Thus in Fig. 2, the block 5 is impressed upon the zones D and D'.

After the strip has been printed, it is cut into separate rugs along the center lines of the pairs of end borders, that is, along the 30 center lines of the zones B and B''. Each rug has a border, and a center figure, and end figures.

To make a shorter center-figure rug design, such as that shown in Fig. 3, a slightly different method is followed. Pairs of impressions of the asymmetric designs of the blocks 2 and 3 with their edges *a* towards each other are made along the strip, but in this case the impressions of alternate pairs are 35 contiguous, while those of the other alternate pairs are spaced apart. Thus in Fig. 3, one pair of asymmetric designs is formed by impressing the block 2 on the zone A and the block 3 on the zone C, while the next 40 pair is formed by impressing the blocks 2 and 3 on the zones A' and C' which are contiguous, and the next by impressing them on the separated zones A'' and C''. Consequently in each alternate pair of impressions, the figures 2^b and 3^b cooperate in forming 45 a center figure 12. The middle spaces of the other alternate pairs of impressions from the blocks 2 and 3 are filled by pairs of end borders. For this purpose, the block 1 50 is impressed on the zones B and B'' in

Fig. 3, so that the figures 2^b, 3^b impressed on the zones A, C, and A'', C'' form end figures in the rug designs.

As before, any space left between the pairs of impressions of the blocks 2 and 3 70 is filled in by impressions of the block 5, for example, on the zones D and D'; and the strip is cut on the center lines of the pairs of end borders.

An important advantage of the set of 75 blocks described is that it may be used—if desired without removing any block from the block printing machine, but merely by adjusting the timing mechanism of the machine—to print symmetrical center-figure 80 rugs of any desired length from three units up, increasing by increments of one unit. The unit referred to is the width of a block which, in a conventional block printing machine, is 18 inches, but which may, of course, be made any amount desired.

Figs. 4 to 11 show rugs of different lengths printed from the set of blocks shown in Fig. 1. These rugs vary in length from three units to ten units, the rug shown in each figure being one unit longer than that shown in the previous figure. The methods of printing these different rug designs are plainly apparent from the figures, as the identifying number of the block impressed 95 upon each zone of each rug shown in Figs. 4 to 11 is indicated at the bottom of each figure. It will, of course, be understood that the block 5 is not used in printing the rugs shown in Figs. 4 to 7.

For the sake of simplicity of description, I have illustrated rug designs printed in one color only, but it will readily be understood by those skilled in the art that the invention may be applied to the printing of multi-colored designs by substituting for each of the blocks 2, 3 and 4 and, if desired, also for the block 5 and the block 1, a set of blocks having figures adapted to form registering impressions. In such case, the fitting of the edges of the asymmetric and symmetrical block designs hereinabove described must, of course, be carried out with respect to the blocks for each separate color. A very simple example of the application of the invention to multi-color work would be to substitute for each of the blocks 2 and 3 a set of three blocks, one carrying the middle figure 2^b or 3^b and the side-border sections 2^a or 3^a, another carrying the intermediate figure 2^c or 3^c, and the third carrying figures adapted to fill in the spaces between the impressions of the border sections, middle figures and intermediate figures. Three corresponding blocks 110 carrying respectively the border sections 4^a and center figure 4^b, the intermediate figures 4^c, and fill-in figures would then be substituted for the block 4, and three corresponding blocks carrying respectively the 115 120 125 130

border sections 5^a, the intermediate figures 5^c, and fill-in figures would be substituted for the block 5.

It will be understood also that asymmetric and symmetrical designs having any desired form and any degree of complication may be, and in practical work ordinarily are, substituted for the simple geometric figures which have been shown for the sake of illustration.

What I claim is:

1. The improvement in the art of printing rugs, which comprises forming a complete end border and an end figure on separate blocks, impressing said blocks side by side to print an end-border design on each rug, and utilizing the one of said blocks having the end figure to print a design at an intermediate part of each rug.

2. The method of making printed rugs from strip material, which comprises printing pairs of oppositely turned asymmetric figures along the strip, the figures of alternate pairs being spaced apart, utilizing the other alternate pairs to form a center figure, printing a pair of end-borders between the spaced figures of the first alternate pairs, and cutting the strip along the center line of each pair of end borders.

3. The method of making printed rugs from strip material, which comprises printing pairs of oppositely turned, spaced apart, asymmetric figures along the strip, printing a fitting symmetrical figure between the figures of alternate pairs to form center figures, printing a pair of end borders between the figures of the other alternate pairs, and cutting the strip along the center line of each pair of said end borders.

4. The method of making printed rugs from strip material, which comprises printing pairs of oppositely turned asymmetric figures along the strip, the figures of alternate pairs being spaced apart, and those of the other alternate pairs being contiguous to form a center figure, printing a pair of end borders between the spaced figures of the first alternate pairs, and cutting the strip

along the center line of each pair of said end borders.

5. The improvement in the art of printing rugs, which comprises providing an asymmetric design and two symmetrical designs whose edges fit the two edges of the asymmetric design respectively, and printing such designs side by side in fitting relation to produce symmetrical rug patterns of different lengths.

6. A set of blocks for use in a block printing machine for printing symmetrical rug designs of different lengths, comprising two blocks carrying the same asymmetric design turned in opposite directions, and two blocks carrying different symmetrical designs whose edges fit the two edges of said asymmetric design respectively.

7. A set of blocks for use in printing bordered symmetrical rug designs of different lengths, comprising a block carrying a pair of end borders which together extend completely across it, and four blocks each carrying side-border sections, two of said blocks carrying between their side-border sections the same asymmetric design turned in opposite directions, and the other two carrying between their side-border sections different symmetrical designs whose edges fit the two edges of said asymmetric design respectively.

8. A set of blocks for use in a block printing machine for printing bordered symmetrical rug designs of different lengths, comprising a block carrying a pair of end borders which together extend across the entire width of the block, and three blocks carrying side-border sections, two of said blocks carrying between their side-border sections the same asymmetric design turned in opposite directions, and the third block carrying between its side-border sections a symmetrical design whose edges fit one edge of said asymmetric design.

In testimony whereof I have hereunto set my hand.

GEORGE PRIFOLD.
